UNITED STATES PATENT OFFICE.

JOHN R. REED, OF WESTFIELD, MASSACHUSETTS.

DESIGN FOR A RADIATOR LOOP-PIPE.

SPECIFICATION forming part of Design No. 20,565, dated March 3, 1891.

Application filed December 9, 1890. Serial No. 374,086. Term of patent 14 years.

To all whom it may concern:

Be it known that I, JOHN R. REED, a citizen of the United States, residing at Westfield, in the county of Hampden, in the State of Massachusetts, have invented and produced a new and original Design for Radiator Loop-Pipes, of which the following is a specification, reference being made to the accompanying drawings, forming part thereof.

- 5 10 Figure 1 in side elevation represents a radiator loop-pipe showing my novel design; Fig. 2, a view of one of the loops looking from the right, and Fig. 3 a view of one of the loops looking from the left.
- 15 The loop-pipe shown has three upright members a b c , and to aid in this description I shall call the member b the "body" and the members a c the "arms." The body resembles a column, and where the body and head and 20 base come together there are annular beads or projections b' b^2 , which indicate that the body might be separate from the head and base. The arms a and c have like annular beads or projections a' a^2 and c' c^2 ; but the 25 projections a' c' are in different horizontal planes. The annular beads or projections or bands a^2 c^2 are likewise in different horizontal planes. The upper end of each loop-pipe presents a sort of head with ears of different 30 lengths, thus making the arms a c appear as

if of different lengths, and it is this appearance which constitutes the leading feature of my design. The upper member of the loop is terminated by an ornamented portion, seemingly distinct from the upright portions, to 35 form a head d , with ears d' d^2 of unequal length. This head is ornamented at 22, and the ears of unequal length are of such configuration or design as to show ornamentation for different lengths, as shown by the ear d^2 , 40 which is represented as longer than the ear d' . The lower end or base of the loop is shown as of such configuration or design, accompanied with ornamentation, as to form pedestals e' e^2 of unequal lengths. 45

The ears and pedestals are shown as provided with scroll and shell or leaf-like figures, the particular lines of which may be varied without departing from my improved design as a whole. 50

I claim—

The design for radiator loop-pipe, as herein shown and described.

In testimony whereof I have signed my name to this specification in the presence of 55 two subscribing witnesses.

JOHN R. REED.
